UNITED STATES PATENT OFFICE

DONALD H. MACBRIDE, OF LAPEER, MICHIGAN, ASSIGNOR, BY MESNE ASSIGNMENTS,
TO INTERNATIONAL TOY CORPORATION, OF NEW BEDFORD, MASSACHUSETTS, A
CORPORATION OF MASSACHUSETTS

DESIGN FOR A TOY OR SIMILAR ARTICLE

Application filed June 25, 1927. Serial No. 22,558. Term of patent 14 years.

To all whom it may concern:

Be it known that I, DONALD H. MACBRIDE, a citizen of the United States, residing at Lapeer, in the county of Lapeer, State of Michigan, have invented a new, original, and ornamental Design for a Toy or similar article, of which the following is a specification, reference being had to the accompanying drawing forming a part thereof.

In the drawing, Figure 1 is a perspective view of a toy or similar article embodying my new design.

Figure 2 is a front elevation of the same.

I claim:

The ornamental design for a toy or similar article, substantially as shown.

DONALD H. MACBRIDE.
